SHIRTS, AND COLLARS, COLLAR BANDS,
AND THE LIKE

Thomas Lewis Shepherd, Brighton, England

Application August 16, 1933, Serial No. 685,477
In Great Britain August 16, 1932

4 Claims. (Cl. 2—127)

This invention relates to shirts and collars, collar bands and the like. As hitherto used these articles of wearing apparel have been made of inextensible material that cannot yield, and they have the further disadvantage that in the course of time they shrink in size. Moreover, such inextensibility in hot weather, for instance, is apt to cause discomfort, and especially when starch is employed in dressing the neck band or collar.

The object of the present invention is to overcome these disadvantages by making a collar, collar band and/or a shirt neck band, in such a way that it or they may yield to all movements of the neck, or to the tensions or stresses occasioned when such wearing apparel is being fastened in wearing position, and in which the collar band or the like will not become creased.

The invention principally consists in an extensible collar, collar band and/or neck band which is made extensible along or adjacent the line or the stud opening or openings, by interweaving or interknitting a number of elastic threads in the fabric.

The invention may be carried into effect in various ways, and the accompanying drawings hereinafter referred to show various embodiments by which the invention may be carried into effect.

The invention will now be described with reference to the accompanying drawings in which:

Figure 1 is a perspective view of the invention as applied to a double or turnover collar.

Figure 2 is a similar view of a shirt neck band made in accordance with the invention.

Figure 3 is a vertical transverse section taken on the line 3—3 of Figure 1.

Figure 4 is a similar section taken on the line 4—4 of Figure 2.

Figure 5 is an enlarged fragmentary view of a weave which is employed when applying the invention.

Figure 6 is a perspective view of a collar according to the invention, which is permanently attached to the shirt.

Figure 7 is a vertical transverse section taken on the line 7—7 of Figure 6, and

Figure 8 is a view similar to Figure 5 of a modified weave.

In one way of carrying the invention into effect as applied in one example to a turn-down, or double detachable collar, and as shown in Figures 1 and 2, the collar consists of two strips of material *a* and *b*, one *a* comprising the outer turn-down side of the collar, and the other *b* consisting of the inside band which comes next to the

neck of the wearer. The outer band *a* is formed of the usual woven or knitted material, so as to match, or not, with the body of the shirt, and is shown in Figure 3 as being formed in two thicknesses as usual. The ends are cut to form turn-down points, and one of such points are shown in Figure 1 as turned up to show the end of the inner band *b*. The inner band *b* comprises one or more thicknesses of material of woven or knitted character, two such thicknesses being shown in Figure 4. In order that this inner band shall be extensible it has, when it is woven, some or all of the warp and/or some or all of the weft threads thereof formed of elastic threads of a suitable degree of thickness, or such threads may be as fine as those of cotton, silk, wool or the like, and may either be left bare or covered with cotton, silk or the like. The upper edge of the inner band *b* is attached as shown at *d* to the turned over edge of the material forming the front or the outer band *a*, so that the two are firmly secured together each along one edge. The free other edges of the inner and outer band are made with a suitable hem so as to form a smooth edge as seen in Figure 3.

The shirt neck band *c* shown in Figure 4 and attached at *e* to the shirt is made in a manner similar to the inner band *b*, i. e. it is made extensible by interweaving or interknitting elastic or rubber threads with the usual non-extensible threads thereof.

The collar thus made may be left either soft or finished with a suitable dressing of starch so that it may possess stiffness. When a soft collar is desired the turn-down points may be fitted as shown in Figure 1 with securing loops or tabs *c*, which are also made with an elastic weave or knit, similarly to that adopted for the body part of the collar.

In constructing such extensible wearing apparel the inner band *b* or neck band *c* is made with all or some of the warp threads, that is to say, those which run longitudinally of the band, of rubber, or may otherwise be rendered elastic. In the enlarged view of the weave shown by way of example in Figure 5, it will be seen that the warp threads *f* are woven with the weft threads *g*, but one in every four of the warp threads *f* is made elastic, as shown at *h* in a thick line, so that the necessary extensibility will be given to the band of material. Although one elastic warp in every four is preferred in most cases, the arrangement is not necessarily limited to this as in other cases a lesser or a greater number of elastic warps may be used. It will, however, be

understood that the degree of extensibility will vary with the number of elastic warps so that the amount of extensibility desired may be controlled by thus varying the number of elastic warp threads that are used. In some cases it may be desired to form some of the weft threads of elastic or rubber; or again some of the warps and some of the wefts may be of an elastic character, so that not only may the amount of extensibility be controlled, but its direction also be influenced.

Referring to Figures 6 and 7, this illustrates the invention as applied to a collar which is permanently attached to the shirt, and, in this case, the inner band *b* is attached by one edge as by sewing at *k* to the top edge *l* of the neck opening of the shirt. The other edge of the inner band is attached as at *m* to the turnover edge of the collar band *c* as shown in Figure 7. If necessary when sewing or otherwise securing the collar bands or parts thereof together, elastic sewing thread may be used. In the two examples shown the end portions of the outer side of the inner band *b* may be tipped or covered as at *n*, with material to match either in color or texture the outer band *a*, so that the shirt and collar present a neat appearance when being worn. In either or both of the foregoing examples the inner and/or outer band may be provided with an insertion between the layers forming the usual reinforcement. If and when desired, such a reinforcing band may be of an elastic character, so as to prevent the formation of any creases, which is of special importance in the outer band.

In a modification the invention may be applied to a collar formed from a single layer of material, and either turnover or not. In such a case it would be made as shown in Figure 8 with weave having a non-extensible zone *o* and an extensible zone *p* formed by the elastic or rubber warps *g*. If used as a double collar the non-extensible zone may be bent over or creased along the line *q*.

It is to be understood that by means of the foregoing invention, great facility will be afforded for securing wearing apparel of the kind referred to in wearing position, because it possesses the characteristic that it is adapted to yield to a stress or strain incidental to the fastening of such apparel in wearing position. Moreover, whilst it is in wear, it will have the advantage that it yields or gives to movements of the body, and thereby increases the comfort in wear, and it is also to be understood that by suitably arranging the number of elastic threads in proportion to the usual linen or non-stretching threads that are used in the construction of the woven or knitted fabric, the amount of give or yield may be controlled; further that this characteristic of extensibility will compensate for any shrinkage that may happen in the wearing ap-

parel after it has been laundered or used for a period of time.

Whilst the drawings illustrate the invention as applied to a collar, which is fitted with a ridge as described in my prior British Patent No. 409,327, it must be understood that the invention is not necessarily limited to such a use, since the invention is also intended to be applied to a collar which is fitted with the usual opening for a back security stud, and the extensibility afforded as above described, will allow of a stretching or a yielding movement in the line of the usual stud openings of the collar, collar band or neck band. Moreover, means are provided whereby a creasing of the collar band is prevented.

Having now particularly described and ascertained the nature of my said invention and in what manner the same is to be performed, I declare that what I claim is:—

1. Improved collar comprising in combination, an outer fold of non-stretchable fabric, an inner fold of permanently elastic stretchable fabric, both folds being attached together along their adjacent edges, a shirt, a neck band thereon of permanently elastic stretchable fabric, and means for securing one edge of the inner fold to the neck band, the elastic stretchable fabric permitting of extension when the inner fold of the collar is being secured in position.

2. Improved collar comprising in combination, an outer fold of non-stretchable fabric, an inner fold of fabric longitudinally permanently stretchable throughout its thickness and the surfaces of which are flat, both folds being secured together along their adjacent edges and a shirt with the neck opening thereof secured to the edge of the inner fold, the arrangement being such that when fastening the ends of the collar, the inner fold may stretch.

3. Improved collar comprising in combination, an outer fold of non-stretchable fabric, an inner fold of permanently elastic stretchable fabric, both folds being secured together along their adjacent edges, a shirt and means for securing one edge of the inner fold thereto in order that the inner fold may be stretched in the direction of its length for the purpose described, having an elastic loop at each end of the outer fold.

4. An improved collar comprising in combination, an outer fold of woven non-stretchable fabric, an inner fold of woven fabric longitudinally permanently stretchable adjacent one edge thereof, and a woven neck band of an associated shirt also of longitudinally permanently stretchable fabric, said fabrics having flat surfaces, so that when the collar is secured in wearing position upon the neck band, the said inner fold and neck band may be stretched for the purpose described.

THOMAS LEWIS SHEPHERD.
